UNITED STATES PATENT OFFICE

169,956

SHOE

Nina Baroumes, Juneau, Territory of Alaska

Application February 20, 1953, Serial No. 23,715

Term of patent 3½ years

(Cl. D7—7)

To all whom it may concern:

Be it known, that I, Nina Baroumes, a citizen of the United States, residing at Juneau, in the Territory of Alaska, have invented a new, original, and ornamental Design for a Shoe, of which the following is a specification, reference being had to the accompanying drawings, forming a part hereof.

I claim:

The ornamental design for a shoe, as shown.

NINA BAROUMES.
